BOWL TYPE OIL BURNER

John G. Behrendt and Louis C. Ruthy,
Chicago, Ill.

Application February 14, 1945, Serial No. 577,835

3 Claims. (Cl. 158—91)

1
This invention relates in general to a liquid fuel burner in which the flames are directed outwardly and upwardly above the burner bowl.

An important object of the invention is to provide a burner assembly in which an air inlet and baffle are arranged to direct air or a combustible mixture in an outward lateral direction over the burner bowl outer wall to produce a wiping action tending to cause a vacuum in the bowl.

A further object of the invention is to provide an air riser and a deflector plate spaced above it to provide a continuous outlet slot causing air to be impelled over the burner bowl for giving impetus to oil vapors from the bowl.

Still a further object of the invention is to provide a burner with a wall sloping continuously downward from its outer edge to a position below the outer edge of the air riser so the bowl will have its maximum depth near the outer circumference of the riser.

Other objects of the invention are to provide improved means for mounting, adjusting, and leveling the burner in a fire-pot or furnace; to simplify the connections between the burner bowl and the air supply pipe; and to provide a simple, effective, and efficient burner which may be readily installed and serviced.

Other objects will appear in the specification and will be apparent from the accompanying drawings, in which,

Fig. 1 is a plan sectional view of a burner in accordance with this invention as taken on the line 1—1 of Fig. 2; and

Fig. 2 is a sectional view as taken on the line 2—2 of Fig. 1.

In many burners of this type, the air for combustion is discharged within or directed into the burner bowl, tending to cause air pressure within the bowl. This may unduly heat the bowl, resulting in a loss of heat or inefficient heating, particularly during a high heat period. The applicants propose to create a partial vacuum in the bowl by the outward blast of air producing a combustible mixture having a flame projected laterally, which for a high heat condition starts above and outwardly of the burner extending to and engaging the side wall of the furnace which is the wall to be heated. Thus the fuel may be said to be burned in suspension.

Referring now more particularly to the drawings, a burner bowl 5 preferably formed of sheet material has an outer marginal rim 6 and an inner surface 7 inclined continuously downwardly and inwardly toward the center thereof to a lowermost portion 8 where it rises to form an upwardly extending ring projection 9 with a sharply bent downwardly extending portion 10 to form a central opening within the bowl. At the bottom of the downwardly extending portion 10 is a clamping ring 11.

2
An air inlet shell 12 is inserted through the circular downwardly extending portion 10 of the bowl and is held tightly within the bowl at any desired elevation therein by the clamping ring 11. The upper edge of the air inlet shell is bent over outwardly to form a projecting edge or rim 13, the top of which is in a horizontal plane, slightly above the elevation of the outer marginal rim 6 of the bowl 5.

Extending downwardly from the air inlet shell and tightly connected therewith is an elbow 14 and a pipe 15 connecting the inlet shell and blower 16 or some other suitable source of air supply.

The projecting edge or rim 13 of the air inlet shell is preferably located directly above the lowermost portion 8 of the downwardly inclined surface of the burner bowl so the space in the bowl decreases outwardly from the lowermost portion to the outer edge of the bowl to assist in producing a partial vacuum in the bowl.

A fuel inlet pipe 17 is inserted through the wall of the bowl to discharge fuel thereinto near the lowermost portion of the bowl. This pipe is ordinarily provided with a magnetic regulator valve 18 and extends to a suitable source of fuel supply. In low fire operation a stable pilot flame will be maintained in a free area close to the air inlet shell 12.

Disposed at the top of the air inlet shell is a flat deflector plate 19 or plate having a flat under surface which is spaced above the marginal rim, and the outer edge of the plate extends outwardly beyond the outer edge of the rim 13 and in the same plane therewith to produce a thin layer of air directed radially outward so that it passes directly over the top of the burner bowl, tending thereby, when the air is under sufficient pressure, to produce a partial vacuum in the burner bowl, and when it is in operation, producing a combustible mixture having a flame projected laterally above and outwardly from the bowl so that the flame is not directed into or against the surface of the bowl.

The deflector plate may be adjustably mounted with respect to the air inlet in any suitable manner as by providing an internally threaded hub 20 connected by legs 21 to the inner wall of the inlet shell at a distance below the top and inserting a threaded bolt 22 thereinto having an outer head 23 and a fixed collar 24 between which the deflector plate is firmly held. By threading the bolt into or out of the hub, the spacing of the plate may be accurately varied and set with relation to the upper edge of the air shell rim 13.

To support the burner in a furnace having a circular wall 25, a flange ring 26 is supported within the furnace at spaced distances by suitable leveling devices, each having a base support 27 with a threaded portion 28 at the top into which a correspondingly threaded rod 29 ex-

3

tends, the upper end of the rod engaging a suitable seat extending at the lower side of the rim 26 and the height of the rod being varied by threading it into and out of the base and securing it in any adjusted position by a lock nut 31 threaded on the rod and engaging the upper end of the support.

A burner of this kind may be easily installed in a furnace or space heater through an ashpit or base opening 32 provided with a closure plate 33 through which the oil and air supply lines are inserted.

With this construction, the combustible mixture produced when air is admitted through the inlet is forced outwardly against the outer bowl wall and above it to produce a wiping action which tends to cause a partial vacuum in the bowl, the combustible mixture having a flame projecting laterally and upwardly so that for any relatively high heat, the flame will engage the outer wall 25 of the furnace, thus burning the fuel not in contact with the surface of the bowl, but held in suspension above the bowl.

Although a preferred embodiment of the invention is thus described, various other changes in the construction, combination, and arrangement of the several parts may be made without departing from the spirit and scope of the invention.

We claim:

1. A liquid fuel burner comprising a burner shell in the form of a bowl having an outer marginal rim and inclined downwardly toward the center, an air inlet shell extending upwardly at the center of the burner shell and having a top rim flared outwardly and terminating at a point above the level of the burner rim, a source of forced air supply for the air inlet shell, a controlled means for discharging liquid fuel into the burner shell adjacent the lowermost point at its bottom, and means to produce a partial vacuum in the burner shell during periods of combustion comprising a deflector supported over and spaced from the rim of the air inlet shell and having its outer periphery extending laterally a distance sufficient to overlie the outwardly flared rim of the air inlet shell and cooperating therewith to provide a circular orifice for discharge of the air substantially horizontally at a level above the topmost point of the burner shell, the deflector terminating outwardly beyond the flared rim of the air inlet shell but at a point substantially close thereto to permit free ascension of the combustible vapors from the bowl in response to the condition of partial vacuum created therein by movement of the air stream radially and laterally over the bowl, whereby the combustion of the fuel vaporized within the bowl is required to proceed in major part outside of the bowl proximate to its outer rim.

2. A liquid fuel burner comprising a burner shell in the form of a bowl having an outer marginal rim and inclined downwardly toward the center, an air inlet shell extending upwardly at the center of the burner shell and having a top rim terminating at a point above the level of the burner rim, a source of air supply for the air inlet shell, a controlled means for discharging liquid fuel into the burner shell adjacent the lowermost point at its bottom, and means to produce a partial vacuum in the burner shell during periods of combustion comprising a deflector supported over and spaced from the rim of the air

inlet shell and having its outer periphery extending laterally a distance sufficient to overlie the rim of the air inlet shell and cooperating therewith to provide a circular orifice for discharge of the air substantially horizontally at a level above the topmost point of the burner shell, the deflector terminating outwardly beyond the rim of the air inlet shell but at a point substantially close thereto to permit free ascension of the combustible vapors from the bowl in response to the condition of partial vacuum created therein by movement of the air stream radially and laterally over the bowl, whereby the combustion of the fuel vaporized within the bowl is required to proceed in major part outside of the bowl proximate to its outer rim.

3. A liquid fuel burner comprising a burner shell in the form of a bowl and continuously inclined downwardly from the outer edge towards the center of the burner, an imperforate air inlet shell extending upwardly at the center of the burner shell and connected at its lower end with the shell at the bottom thereof, and having its upper end extending above the bowl, said burner shell and air inlet shell forming a hollow annular chamber, means for discharging liquid fuel into said chamber, and means for creating a partial vacuum in the chamber during periods of combustion, including a pressure source of air supply for forcing air upwardly through the air inlet shell, and a deflector located adjacent to and spaced from the upper edge of the air inlet shell and projecting laterally beyond the same and also located above the horizontal plane of the upper edge of the burner shell, said deflector and burner shell cooperating to form an annular opening for directing a layer of air under pressure over the upper edge of the bowl for producing a wiping action thereon tending to create a partial vacuum within the bowl resulting in a mixture of air and fuel vapor and a flame projected laterally above and outwardly from the bowl.
